ELECTRIC SWITCH

Victor R. Despard, Syracuse, N. Y., assignor to
 Pass & Seymour, Inc., Syracuse, N. Y., a corpora-
 tion of New York

Application April 6, 1934, Serial No. 719,383

12 Claims. (Cl. 200—67)

This invention relates to electric switches and particularly to switches of the type used in the wiring of residences, stores, office buildings, and the like, mounted behind wall plates and used 5 mainly for the control of lights, small motors, and household appliances.

The invention is particularly applicable to switches of the type intended for use in combination assemblies of wiring devices or multiple 10 units of switches as particularly disclosed in my Reissue Patent No. 19,092, granted February 20, 1934, and provides improvements in such switches for that purpose as shown in the patent to Russell and Despard No. 1,948,399, granted February 20, 15 1934.

It is a general object of the present invention to provide, in such switches, novel and improved mounting means for the contacts and terminals thereof.

More particularly it is an object of the invention to provide means whereby the closure plate, which is formed of insulating material, takes part 20 of the strain of the wiring as applied to the terminals and relieves, to that extent, the housing of the switch which, by virtue of its peculiar size and shape limitations, is relatively fragile.

Another feature of the invention resides in the construction of a snap switch including an insulating housing having an open rear for the 25 insertion of switch operating mechanism and switch contacts, together with supporting means for these contacts and their associated terminals, which means are carried jointly by the housing and by an insulating closure for the rear thereof.

Other and further features and objects of the invention will be more apparent to those skilled in the art upon a consideration of the accompanying drawing and following specification wherein are disclosed several exemplary em- 30 bodiments of the invention illustrating the generic scope thereof. It will be understood that such changes and modifications may be made in the various features illustrated such as fall within the scope of the appended claims without de- 35 parting from the spirit of the invention.

In said drawing:

Figure 1 is a side elevation, partly broken away, of a switch constructed according to the present invention shown assembled in a mounting strap; 40 Figure 2 is an end elevation thereof having a portion broken away to illustrate the connection of the terminal carrying plate and the closure; 45

Figure 3 is a rear elevation thereof with a portion of the closure and its securing means broken away;

Figure 4 is an elevation of a contact and terminal carrying plate;

Figure 5 is a view similar to Figure 1 illustrating a different embodiment of the invention;

Figure 6 is a view similar to Figure 3 but illustrating the embodiment of Figure 5; and

Figure 7 is a view similar to Figure 4 illustrating a modified form of contact and terminal carrying plate and its associated parts.

In the above identified reissue patent there is disclosed a system of arranging and mounting wiring apparatus of the type referred to, wherein a plurality of wiring devices are assembled in the space usually occupied by a single one, specifically, three wiring devices in the conventional space allotment of a single gang outlet box. At times all three of these devices may be switches, which requires that each individual switch should conform to very definite space limitations. Nevertheless each switch must be able to handle relatively high currents and comply with the quite rigid specifications of the Underwriters' Laboratories. Such switches as now constructed are capable of handling sufficient current to require connecting wires as large as No. 12 B. & S. gauge. Such wire is relatively stiff and unyielding and is attached to switches in their assembled form on mounting bridges prior to the insertion of the assembly into the outlet box. There results a considerable strain on the terminals and their supporting means when the assembly is inserted into the box because the wires are always sufficiently long to permit wiring outside of the box and must then be bent and stowed in the box as the assembly is moved into position. The bending results from pressure on the assembly and resistance at the attachment of the wires to the box wall. Sometimes the bends are quite short and the strains considerable. It has been found that where the switch shell or casing, which is formed of molded insulating material, is solely relied on to take the strains, breakage sometimes occurs, particularly since the space limitations are such that the shell cannot be made as strong as manufacturers would like.

It has been found that the rear end of the shell, which takes the major strain, is the part that most often succumbs to it, so in accordance with the present invention a portion of this strain is transferred to the closure plate to be more uniformly applied to the shell, and localized strains resulting in cracking are largely eliminated.

Referring now to the drawing and particularly to Figures 1-4 inclusive, there is shown at 10 a mounting strap of the type intended to span the

open face of an outlet box and to be secured thereto. It may support from one to three wiring devices which are attached thereto, preferably interchangeably, in any desired manner. A single switch is shown attached to the strap.

The switch is assembled within a shell 12 of insulating material. This shell includes a front wall 13 having a neck 14 which fits through an aperture in the strap 10 and may have a portion 15 to extend through the face plate (not shown). This front wall 13 and the neck are perforated for the passage of the switch operator 16, which in this instance operates a mechanism of the toggle type.

15 Integral with the front wall 13 are the two side walls 17 and 18 and the end walls 19 and 20, meeting each other at substantially right angles whereby cross sections of the switch housing in planes parallel to that of the strap 10 are substantially rectangular. The side and end walls terminate in a plane 21, and the rear of the casing or shell is open, permitting access to the interior.

Switch mechanism of suitable form, for instance as shown in Patent No. 1,948,399, is insertable through the rear opening of the shell with its handle 16 passing through the opening in the front wall, and is mounted therein in any desired manner, preferably by having a lug at the front engage in a suitable notch in the shell and by having the rear supported as will be herein-after described. This switch mechanism carries an insulating sector plate 22 adapted to be oscillated from one position to another by the action of the snap mechanism manipulated by the handle 16. This sector carries contacts or bridging members as required by the nature of the circuits to be controlled by the switch, and these movable contacts cooperate with at least a pair of stationary contacts.

40 While the switch may be constructed for single-pole, double-pole, three-way, and four-way operations as shown in the patent just referred to, to the present invention, for the sake of simplicity, is shown as applied only to single-pole switches but is not to be so restricted.

45 In the single-pole construction, a pair of stationary contacts 23 is provided, each being substantially U-shaped as seen in Figure 3 and having arms which straddle the sector plate and serve to prevent its movement except in its own plane. These contact members extend from substantially the rear edges of the end walls toward the center of the shell, as clearly seen in Figure 1, and each is mounted on a metal plate or carrier 50 shown in detail in Figure 4. It is a plate of metal having a substantially uniform width considered in the fore and aft direction of the switch, where the handle is the front, and having squared ends 26. As best seen in Figure 3, it is off-set as at 55 intermediate its ends so that the portion 28 which carries the contact is higher than the portion which receives the terminal screw 30.

The switch is preferably assembled without fastening means to hold the various parts individually in the housing, and each plate 25 is insertable from the rear of the housing with its ends received in slots in the side walls, each extending from the rear of the housing forwardly closely adjacent an end wall. One of these slots is shown 60 at 31 in Figure 3 and is of sufficient length to receive the whole width of the contact plate. The other slot 32 is mainly defined by abutment 33 but near the forward edge of plate 25 has an outer abutment 34 seen at the left side of Figure 3 where a portion of the housing is broken away.

The rear portion of the abutment is absent because of the relatively large notch 35 cut in the end housing wall from the rear to expose the head of the terminal screw 30 and the portion of the plate 25 surrounding it and including the struck-out lug 36 for positioning the wire under the terminal screw. 5

To retain the switch assembly, as well as the mounting plates 25 in the housing, the open rear is covered by a closure member 38, preferably formed of laminated insulating material to have considerable tenacity. It has a configuration similar to the rear of the housing but is preferably cut away over the notches 35 to provide better access to the terminals from the rear, in which direction the wires extend. Openings 39 in this closure plate receive lugs, on the rear of the switch mechanism, to position the same while the closure plate itself directly engages the rear edges of the plates 25, as clearly seen in Figure 20 2, and holds these plates in their grooves so that they are thus prevented from moving in any direction. This closure 38 is secured to the shell in any convenient manner, as for instance by the overlying metal plate 40 of lesser area having the turned-down arms 41 passing through notches in the closure and having the ends expanded into grooves in the side walls of the shell. In this manner the closure plate is securely fastened to the shell, and the attachment is at the center 30 of the side walls where they are strongest.

To prevent cracking of the shell, particularly at the rear corners, means are provided to impart certain of the strain on the plates 25 to the strong rear closure plate 38, and this is done by extending rearwardly from plate 25 a lug 42, as seen in Figures 1, 2, and 4, and forming in the closure 38 a snugly fitting recess to closely engage this lug, in this manner providing for the transfer of the strain from the corners, at least to the centers of the side walls, through the attachment of the closure plate thereto. The lugs 42 are, of course, live and can be protected if desired by a projection 43 of insulating material from the cover plate. 45

In the embodiment just described it will be seen that the plates 25 are carried jointly by the shell and the cover plate and can be said to have their forward portions associated with the shell and their rearward portions with the closure. 50

In the embodiment shown in Figures 5-7 inclusive, the essential features of the switch and shell are identical with that just described, but the contact and terminal supporting means are somewhat differently arranged. In the first described embodiment, the contacts and terminals are directly secured to metal plates which are mounted in slots in the side walls of the shell adjacent the end walls thereof. In the second form of the invention, the carrier for the contact and terminal at each end of the shell may be of insulating material in the form of a substantially rectangular plate 50 shown in Figure 7, and this is set into the shell through the rear and parallel to the adjacent end wall. This plate may be provided on its outside face with a strap 51 of metal, riveted or otherwise secured thereto and having a turned-up lug 52 to cooperate with the terminal screw 53, threaded in the strap, for holding the wire in position. 55

The contact 54 has its central portion abutting the inside of the plate 50, and a rivet may be passed through the contact, the plate, and the strap 51 to secure them together mechanically and to provide the electrical connection between 70

the terminal and the contact. Instead of this assembly being mounted in slots in the side walls of the shell, its forward edge has engagement with the shell or a projection on the shell. Conveniently this may take the form of one or more lug-like projections 55 extending from the forward edge, which projections are received in recesses 56 formed in bosses 57 molded integral with the end walls of the shell as seen in Figure 5.

10 The rear edge of this insulating plate 50 carries one or more lug-like projections 58 which are received in openings 59 in the cover plate 60 which may be attached in the manner previously described. The end walls 61 of the shell are 15 notched as at 62 to expose the heads of the terminal screws, and corresponding notches 63 are cut in the closure plate. These are true notches rather than a removed corner, as in the first embodiment, and leave material for a pair of the 20 lugs 58 to be received.

In this embodiment, as in the first one, it will be seen that the forward end of the contact carrier is attached or mounted in the housing whereas the rear edge thereof is secured to and 25 positioned by the closure plate. In this manner substantially all strain from the rear edges of the walls of the housing is eliminated. Where the attachment of the forward edge of the contact carrying plate is made, the housing naturally has greater strength by reason of its association with the front wall.

It will be appreciated that where the invention of the first embodiment is applied to such switches as have more than one contact at each 35 end, as in the double-pole, three-way, and four way types, only the rearmost contact carrier plate will have a lug engaging the closure plate, but in the event of using the embodiment of Figures 5, 6, and 7, the insulating carrier plate 40 can be provided with two sets of terminal screws and two contacts which will, of course, be insulated from each other. A further advantage of the construction of Figures 5, 6, and 7 is that where a double contact assembly is provided, it 45 can be inserted without removing the forward terminal screw which is exposed as shown in Figure 7 of Patent No. 1,948,399 through an opening in the end wall not connected with the rear opening in the shell. This cannot be done where 50 the supporting plates are slid into grooves as in that patent.

The necessary changes in the devices as shown to accommodate them to other than single-pole contacts will be obvious from an inspection of Patent No. 1,948,399.

Having thus described the invention, what is claimed as new and desired to be secured by Letters Patent is:

1. In a switch of the type described, in combination, a shell of insulating material having side walls, a front wall perforated for a switch operator, and an open back, a contact and terminal screw support near one end of the shell, interengaging means on the support and shell 65 to position one end of the support means in the shell, a closure sheet of insulating material for the rear opening of the shell, means securing said closure rigidly to the shell, said closure sheet having a recess pressed into its under surface and a projection on said support fully and closely housed in said recess to position the opposite end of the support in respect to the shell.

2. In a snap switch, in combination, a shell of moulded insulating material having side walls, 70 end walls, a front wall and an open back, a

closure plate for said back formed of tenacious insulating material, means to securely fasten said plate to said shell, a contact carrying member extending along each end wall and having a part cooperating directly with said shell for support thereon, another part of said member entering said plate a distance less than the thickness of the plate for cooperation therewith.

3. In a snap switch, in combination, a shell 10 of molded insulating material open at its rear for the insertion of switch mechanism and having a front wall, side walls and end walls, an insulating cover plate adapted to be securely fastened over said open rear, a contact and terminal support adjacent each end wall, a portion on each support engaging in a recess in the shell, a portion on each support engaging in a close fitting recess in said cover plate, said cover plate having other engagement with the supports to maintain them in the shell, each support having a switch contact and a terminal screw member associated therewith.

4. In a snap switch of the type adapted to be assembled with two other wiring devices in 25 the space of a single gang outlet box, in combination, a shell of moulded insulation adapted to be assembled with a mounting strap, said shell being substantially rectangular in sections parallel to the plane of said strap and including 30 a front wall, connected side and end walls and an open rear, a cover for the rear adapted to be secured to the shell, a support mounted in the shell substantially parallel to and near each end wall thereof, a contact and a terminal screw 35 on each support, means on each support received in otherwise closed recesses in the shell and cover to retain the support rigidly in position, a notch in each end wall for access to the terminal screw on its associated support, and switch 40 mechanism in said shell to cooperate with the terminals on the supports.

5. In a snap switch, in combination, a shell of molded insulating material having side walls, end walls, a front wall perforated for a switch 45 operator, and an open back, a groove extending from the back toward the front in each side wall adjacent one end wall, a contact support member extending from groove to groove across the shell, a terminal screw carried by said support, 50 an opening in the adjacent end wall for access to said terminal screw, a switch mechanism having a frame in said shell, a closure of insulating material for said back opening, means securing said closure firmly to the shell, a lug on 55 said support member, and a recess in said closure snugly receiving said lug, said closure engaging another portion of the contact support member and the frame to hold them in the shell.

6. In a snap switch, in combination, a shell of insulating material having side walls, end walls, a front wall perforated for a switch operator, and an open back, a groove extending from the back toward the front in each side 65 wall adjacent each end wall, a contact support member extending from groove to groove across the shell adjacent each end wall and slideable into position through the open back, a contact 70 on each member extending toward the interior of the shell, a notch in each end wall communicating with the open rear of the shell, a terminal screw projecting outwardly from each member and received into said notch as the member is slid into position, a closure for said rear 75

- shell opening engaging said members to secure them in the grooves, and means on each member and the closure cooperating to connect the members together through the closure and relieve the lateral strain on the grooved walls resulting from wires attached to the terminals.
7. In a snap switch, in combination, a shell of insulating material open at its rear for the insertion of a switch mechanism, sides on said shell grooved longitudinally of the shell adjacent the ends of the shell, a terminal supporting plate extending adjacent each shell end and having its ends in the opposing grooves, a closure of insulating material for the rear opening of the shell engaging the rear edges of the terminal supporting plates to hold them in the grooves and shell, a lug extending rearwardly from the rear edge of each plate, and an opening in the closure to closely engage each lug.
8. In a snap switch, in combination, a shell of insulating material having side walls, a front wall and an open back, a groove extending from the back toward the front in each side wall near each end thereof, a contact carrying plate extending across each end of the shell and each having its ends in opposing grooves, a contact extending inwardly from each plate, a terminal screw on the outer side of each plate, a lug projecting rearwardly from the rear edge of each plate, and an insulating cover secured to the rear of said shell, engaging the rear edge of each plate to hold it in the shell and having a recess to wholly receive each lug.
9. In a switch of the type described, in combination, a shell of insulating material having side walls, a front wall perforated for a switch operator and an open back, a contact support near one end of the shell, means integral with said shell receiving the forward edge of said support, a closure of insulating material secured over the rear opening of said shell, means on the rear of said support extending into said closure whereby the support is fixed at opposite edges in re-
- spect to the shell and a terminal screw extending into said support.
10. In an electric switch, in combination, a shell of insulating material having an apertured front wall and an open back for the insertion of switch mechanism, a combined contact and wire terminal device within the shell and adjacent an end thereof, the wire terminal portion of the device being accessible through an opening in the said end of the shell, a portion of said device engaging in a recess in the shell, said device having an extension reaching beyond the plane of the back of the shell, a closure plate for the open back of said shell having engagement with said extension, and means holding said plate to said shell.
11. In a snap switch, a shell of insulating material having side walls, a front wall perforated for a switch operator and an open back, a closure plate secured over said open back, a compound wire terminal and contact supporting device extending along an end wall of said shell, a part of said compound device extending into a recess formed in said shell, another part of said compound device extending rearwardly and engaging in a recess in said closure plate, a terminal screw and a contact mounted on said compound device, the engagement of said parts within said shell and closure plate recesses holding said compound device in position in the end of the shell.
12. A snap switch comprising an insulating casing having parallel side walls, an operating handle projecting from said casing, a plurality of fixed and movable contacts in said casing, a flat sheet of insulation insulating one movable contact from another and spaced from said side walls, snap mechanism causing relative, simultaneous snap movement of said contacts along the opposite surfaces of said sheet of insulation, a cover for said casing, said cover and casing jointly positioning said fixed contacts.

VICTOR R. DESPARD.
